VACUUM DISTILLATION OF OILS

Golden A. Moyer, Bartlesville, Okla., assignor to Phillips Petroleum Company, a corporation of Delaware

Application October 23, 1952, Serial No. 316,411

8 Claims. (Cl. 196—77)

This invention relates to the vacuum distillation of oils. In one aspect this invention relates to a process for the vacuum distillation of heavy hydrocarbon oils. In one aspect this invention relates to apparatus for carrying out the vacuum distillation of oils. In another aspect this invention relates to a step of withdrawing a portion of residuum product from a vacuum distillation zone and admixing same with oil feed previously heated at an elevated temperature for charging to the vacuum distillation zone, so as to prevent incipient cracking of the heated oil on the way to the distillation zone, by quenching, and to provide a heat carrier to increase the total heat available in the initial flashing operation in the vacuum distillation zone, whereby depth of flash is increased without increasing temperature of the oil feed. In still another aspect this invention relates to a step of recovering condensed product of vacuum distillation and returning a portion of same to the distillation zone together with fresh feed and passing a remaining portion to a predetermined utility under carefully controlled constant flow rate conditions.

Heretofore in the vacuum reduction of residual oils, distillate fractions having high carbon residues have been obtained, together with residual pitch or tar fractions in high yield, i. e., as for example from 50—70 volume percent of residue based on the total oil charged. Furthermore, the distillate fractions thus recovered are "dirty," that is, they are high carbon residue oils containing heavy carbonaceous materials present as a result of the entrainment of such materials in the vapors during the vacuum distillation. Such high carbon residue gas oils are undesirable as feed stock for various conversion processes. Furthermore, when employing conventional oil-reduction operations some of the gas oil components of the oil charge are lost to the distillation residue at the expense of gas oil yield.

Reduction of the pitch or tar yield depends to a large extent upon the high temperature and low pressure conditions that can be maintained during the initial flash distillation or reduction step. The maximum flash temperature is limited by cracking of the heated oil with concomitant gas formation and increased distillation pressure, these resulting conditions in turn causing a decrease in reduction efficiency. It is therefore highly desirable that a maximum flash temperature be achieved without the occurrence of cracking, in order to facilitate a maximum depth of flashing, and in order to produce maximum yields of distillate product and lowest possible yields of residuum.

This invention provides for the vacuum reduction of heavy oils under maximum distillation temperatures that can be employed without oil cracking and under minimum operating pressures and for the recovery of gas oil distillate fractions particularly suitable as feed stocks for various conversion processes, in higher yield, and for concomitant lower yields of pitch product, than have been obtained heretofore.

In accordance with a broad embodiment of this invention, a heavy oil, as for example a topped crude or a

2

residuum from a topped crude cracking operation or a mixture of such heavy oils, having been heated to a temperature required for flashing same in a vacuum distillation zone, as for example 600—900° F., is introduced into a flash or first section of an elongated distillation zone maintained at an over-all absolute pressure generally below from 0.1 to 15 mm. Hg and often as low as from 0.01 to 1.0 mm. Hg. The heated charge upon being introduced into the first section is flashed, with the highest boiling components of the charge material remaining unvaporized, these unvaporized materials comprising residual pitch, a major proportion of which settles as liquid in the first section. A small portion of unvaporized material is entrained in the flashed vapors as small, finely divided droplets. Vapors containing entrained liquid droplets are passed from the flash section through a baffle into and through a second section downstream from the flash section and adjacent thereto, wherein at least a portion of the entrainment settles as residual liquid product. Liquid product in the second section contains settled entrainment and at least a portion of any condensate that may be formed in the said section by radiation. Vapors are passed from the second section into a downstream or third section, adjacent to it in contact therein with a spray of cooler oil to effect partial or substantially complete condensation of vapor as desired. When only partial condensation is effected, the vapors are passed against the flow of atomized oil droplets so as to condense the vapor on the oil spray and as separate droplets, the oil spray having a momentum at least as high as that of condensate formed in contact therewith so as to cause the total condensate to settle in the contacting section. Uncondensed vapors from the said third section are then passed into an adjacent or fourth section and completely condensed therein. If desired, additional partial condensation steps can be employed prior to effecting the final and complete condensation. Although when effecting total condensation as described above, alone or in conjunction with a prior partial condensation step or steps, it is not required that the sprayed droplets be directed against the vapors contacted therewith, contacting the vapors against sprayed droplets under momentum conditions as discussed above is preferred because in this manner the problem of condensate recovery is simplified and the loss of condensate to the vacuum system is greatly minimized. Further, passage of any condensate into the vacuum system markedly decreases the efficiency of the vacuum producing means thereby preventing attainment of minimum distillation pressures.

My invention is further described with reference to the attached drawing which is a diagrammatic flow sheet illustrating one embodiment of a process of my invention and also setting forth vacuum distillation apparatus of my invention. Referring now to the drawing, inlet conduit 9 extends into end section I of closed elongated shell 10, heavily insulated by external insulation means 11, and terminates therein in a direction toward the shell end 12. A wire mat 13 is transversely disposed in shell section I intermediate the outlet end of conduit 9 and shell end 12. Baffle 14 in shell 10 transversely closes same and terminates shell section I. Baffle 16 in shell 10 transversely closes same, is disposed intermediate baffle 14 and shell end 17 and terminates shell section II, the remaining portion of shell 10 constituting section III. Spray nozzle system 18 in section III comprises separate nozzle assemblies 18a, 18b, and 18c, each nozzle assembly being directed to deliver spray toward baffle 16; nozzle assembly 18a being disposed in closest proximity to baffle 16, nozzle assembly 18c being furthermost from baffle 16 and nozzle assembly 18b being disposed intermediate assemblies 18a and 18c. Conduit 19 is connected with the interior of shell 10 through mist extractor system 21 in

section III at a point intermediate spray assembly 18 and shell end 17, and extends from shell 10 to an external vacuum producing means, as for example a steam jet system 22.

Conduit outlet means in shell 10 comprises surge vessels 23, 24, and 26, respectively connected with sections I, II, and III, to receive materials discharged from each said section. Each surge vessel, i. e., 23, 24, and 26, is respectively equipped with conventional liquid level control mechanisms, 27, 28 and 29, for regulating flow of liquid from the surge vessels through respective motor valves, 31, 32 and 33. Conduits 34, 36 and 37 are connected respectively with spray assemblies 18a, 18b, and 18c and with header conduit 38 and are equipped respectively with conventional flow recording controllers 39, 41 and 42 for regulating flow of liquid through motor valves 43, 44, and 46. Conduits 47 and 48 are connected respectively with surge vessels 26 and 23 and are each equipped with conventional flow recording control means 49 and 51 for regulating flow of liquid through motor valves 53 and 52, respectively.

Baffles 14 and 16 can be of any suitable design, such as for example a plurality of overlapping plates, a plurality of plates in separate planes containing openings offset from those in an adjacent plate, a system of overlapping angle members, or the like, it being important that the baffle provides for off-set openings necessitating a tortuous path for vapors passed therethrough, it also being necessary that the offset openings are of sufficient size so as to not develop an undue pressure drop therethrough. One suitable form of baffle 14 and 16 constitutes a system of angle irons comprising two parallel groups, i. e., a double row, of interlocked angle irons, each group comprising a plurality of elongated spaced members (angle iron) the central or spaced portions of all members in one group facing those of the other, and overlapping so that the adjacent edges of any two adjoining members in each group converge toward the central or face portion of a member in the opposite group, thus directing vapors first into the central or face portion of a member of the opposite group and then in a double reverse direction into the adjacent downstream section in the chamber, thereby providing for offset openings and a tortuous path for vapors therethrough.

Dams 15 and 20 are associated, respectively, with baffles 14 and 16, along a bottom portion of shell 10 to prevent flow of settled liquid from one shell section into another. When employing baffles of the interlocked angle iron type described above, the dam is preferably disposed between the two parallel groups or rows of angle irons.

Other apparatus of my invention is disclosed in the following description of one embodiment of the process of this invention.

Again referring to the drawing, a heavy hydrocarbon oil such as a cycle oil resulting from distillation of product of catalytic cracking, from line 54 together with topped crude from line 56 and steam from line 57, is charged into line 58 and then into heater 59 wherein it is heated to a temperature within the range of about 600-900° F. under a pressure generally approximating atmospheric pressure and not exceeding about 100 p. s. i. g. Heated oil is discharged from coil 61 in heater 59 through line 62 into hot oil separator 63 wherein light ends present in the heated liquid are separated and vented through line 64. Steam from line 66 is admitted to separator 63 to strip vapors from the liquid therein, and is withdrawn together with vapors through line 64. Separator 63 is operated under oil flashing conditions.

Unflashed oil in separator 63, heated to a temperature at which incipient cracking may occur, is quenched just sufficiently to prevent incipient cracking but to permit the oil to be at its maximum non-cracking temperature. This quench is effected by introducing oil residuum distillation product as described hereinafter, in admixture with unquenched oil in separator 63. Unflashed oil,

containing residual distillation product admixed therewith, is withdrawn from separator 63 at its predetermined high temperature through line 66 and passed into line 9 and then into section I of vacuum distillation chamber 8 under flashing conditions against wire mat 12, either from the open end of pipe 9 or from a spray nozzle 9a attached in section I to pipe 9. In this manner, charge emitted toward mat 13 in section I is caused to suddenly reverse its direction of flow, and separation of unvaporized portions from the vaporized portion is thereby greatly accelerated, and droplets not vaporized coalesce on the mat with a minimum of splashing, thereby lessening the amount of liquid entrained in the vapors. Discharge of oil against wire mat 13 in this manner also causes unvaporized droplets to flow against the flow of hot vapors, which facilitates further vaporization of those liquid charge droplets, thus further providing for a decreased yield in residual unvaporized charge, and for increasing the yield of lighter gas oil distillate.

A portion of unvaporized oil settles in section I as residuum or pitch product. Residuum from section I is discharged into surge drum 23 and in part returned as quench to separator 63 at a controlled predetermined constant rate of flow through motor valve 52 in response to flow recorder controller means 51. Quench oil from valve 52 is passed into a lower portion of the oil body in separator 63, either through line 67 or 68, the latter being preferable. In this manner the unflashed oil in separator 63 is quenched to a temperature such that incipient cracking of this oil is prevented and thus does not take place while oil is on its way to the distillation chamber 8 via line 9. The rate of quench oil flow is regulated to provide maximum temperatures of oil withdrawn from separator 63, without incipient oil cracking taking place. Generally from 0.2 to 1.5 volumes of liquid quench is charged to separator 63 per volume of unflashed oil withdrawn therefrom. Quench oil added in this manner to separator 63 also serves to act as a heat carrier during the initial flashing step in section I of chamber 8, thus providing for an increase in total heat available in the flash section and thereby for an increase in depth of flashing ordinarily obtainable only at higher feed temperatures. In conducting the quench, I have found it to be advantageous to maintain the separator 63, or at least the portion thereof at its outlet, as an upright elongated vessel, and for introducing the oil quench into a lower portion thereof to prevent any vapors whatsoever, formed by incipient cracking, to escape into line 9 and ultimately reach vacuum jet 22, thus preventing overloading of the jet and maintaining minimum operating pressures.

As a means for effecting further control of oil temperature in separator 63, if desired, a sidestream of oil from line 66 can be recycled through motor valve 71 in response to temperature recorder controller means 70, line 69, cooler 72, and line 48 to separator 63, to thereby supplement control and maintenance of the predetermined, constant distillation feed temperature.

Vapors in section I containing entrained liquid droplets, are passed downstream through baffle 14 into shell section II, wherein some condensation takes place by radiation, and, due to residence time of vapors therein at least a portion of entrainment therein settles as liquid product. Vapors freed from at least a portion of entrainment in section II are passed downstream through baffle 16 into section III in contact therein with a cooler oil spray from spray nozzle assembly 18, maintained at a temperature sufficiently lower than that of vapors contacted therewith so as to effect total condensation by heat exchange. Temperatures from 80 to 300° F. are generally preferred.

Preferably, vapors are contacted against a flow of sprayed oil in section III, while maintaining the momentum and directional flow conditions of the sprayed

droplets as described above. When not employing the cooler spray under the described flow and momentum conditions, settling of condensate in section III is somewhat more difficult, i. e., some liquid condensate droplets may by their own momentum find their way into vacuum jet means 22 in which case efficiency of the vacuum producing means is greatly impaired and concomitant high operating pressures are encountered with accompanying decrease in vacuum distillation efficiency.

Vacuum distillation zone 8 is maintained under sub-atmospheric pressure by operation of vacuum jets 22, preferably steam jets, in direct communication with shell section III at a point downstream from spray nozzle assembly 18, via mist extractor 21.

Liquid product of distillation is withdrawn from sections II and III, respectively, into surge vessels 24 and 26. Product from surge vessel 24, comprises "dirty" gas oil and is advantageously recycled through motor valve 32 in response to liquid level controller 28 via line 73 to heater 59, i. e., together with fresh feed, and ultimately to vacuum distillation chamber 8.

The portion of oil residuum product in surge vessel 23 not returned to separator 63, is passed through motor valve 31 in response to liquid level controller 27 via line 74 to a further utility not shown.

Condensed liquid distillation product in surge vessel 26 is particularly suitable as feed to various hydrocarbon conversion processes, and is withdrawn in a major proportion through line 76 and passed through line 47 and through motor valve 43 in response to flow recorder controller means 49 at a carefully controlled rate of constant flow to a catalytic cracking step as feed thereto. This control of gas oil flow through line 47 to catalytic cracking is particularly of great importance when the said catalytic cracking is a TCC cracking system, the latter requiring an accurately controlled feed inlet flow rate; thus if the stream flowing in line 47 were regulated in response to a liquid level control means, for example liquid level controller 29, the flow to the catalytic cracker would vary slightly with change in composition of feed to the furnace or with furnace temperature or other factors, which variance would be undesirable.

A proportion of the liquid product in surge vessel 26 is recycled via line 38 to lines 34, 36 and 37 and cooler 40 as cooled feed to spray nozzles 18a, 18b and 18c. Pre-determined rates of flow of oil through each of lines 34, 36, and 37 are maintained through motor valves 43, 44, and 46 respectively, in response to flow recorder means 39, 41, and 42, respectively. Oil feed to spray assembly 18c is additionally cooled, upon being passed through cooler 45, to insure sufficient final cooling, when necessary, to effect total condensation. Remaining oil product in surge vessel 26 is passed through motor valve 33 at a rate controlled in response to liquid level controller 29, via line 30 to heater 59 together with fresh feed, and ultimately to vacuum distillation zone 8. This latter stream is generally a relatively small proportion of product withdrawn from surge vessel 26.

When desired, distillate recycled in line 30, or gas oil recycled in line 73, or both, can be passed to heater 83 through lines 81 and 82 respectively and heated therein and then admixed with heated feed in line 62.

By the arrangement of baffles and condensing sprays in the distillation system as disclosed herein, a lower pressure drop across the chamber is achieved, than heretofore possible, for example a pressure drop across the vessel 8 is generally in the order of about 0.3 to 4.0 mm. Hg. Accordingly, higher vacuum is obtained than heretofore possible, the over-all operating pressure being generally within the limits of 0.05 to 10 mm. Hg. Further, by the novel step of recycling residuum to the hot oil separator as a distillation feed quench and as a heat carrier, as described hereinabove, maximum possible flash feed temperatures (without cracking) are achieved, and greater depth of flashing is effected than obtainable at a given

temperature of feed in the line to the flash zone without recycle of residuum.

The method and apparatus of this invention are particularly suited for application in methods and apparatus as described and claimed in the copending applications Serial No. 188,604 filed October 5, 1950 of V. C. Cavin et al., now abandoned and Serial No. 241,183 filed August 10, 1951 of Paul M. Waddill, now abandoned.

In accordance with process and apparatus disclosed in application, Serial No. 188,604, a heavy oil is vacuum distilled by first flashing it so as to effect partial vaporization; removing entrained liquid droplets from vapors thus formed, by passing the said vapors against an impinging oil spray maintained at a temperature and under momentum conditions so as to cause settling of the entrainment with substantially no condensation of the vapors; thereafter condensing resulting liquid-free vapor in contact with one or more cooler impinging oil sprays maintained under momentum conditions to cause settling of condensate formed, or by contacting such liquid-free vapors first with a cooler condensing surface and then with an impinging oil spray to settle the condensate formed. In another embodiment, residuum recovered from the flashing step is further reduced in a second stage, in a separate vessel employing entrainment removal and condensation steps similar to those of the first stage.

In accordance with process and apparatus disclosed in application, Serial No. 241,183, a heavy oil is vacuum distilled by flashing, removal of entrainment, and subsequent condensation, in accordance with the process and apparatus of Serial No. 188,604 except that a second stage distillation of first stage residuum product is effected in the same vessel in which the first stage reduction is effected, or in a separate vessel, in either case utilizing only one source of vacuum, this latter feature being possibly by taking advantage of the inherent pressure drop across the first stage distillation zone. Supplemental heating of residuum charged to the second stage distillation can be dispensed with. Distillation temperatures lower than employed heretofore are provided, while maintaining the pressure substantially unchanged, by dispersing the oil feed in a highly finely divided state.

Variation and modification are possible within the scope of the foregoing disclosure, drawing, and the appended claims to the invention, the essence of which is process and apparatus for effecting vacuum distillation of heavy oils; applicant's process comprising introducing a heated heavy oil into a first and upstream-most section of a substantially horizontal elongated distillation zone under flashing conditions causing partial feed vaporization, passing vapors containing entrained droplets of unvaporized feed downstream through a baffle into and through an adjacent and second section wherein condensation of vapors can take place by radiation and some entrainment may settle from the vapors together with condensate, passing vapors from the said second section through a baffle downstream into an adjacent and third section in contact with a spray of cooler oil to effect substantially total vapor condensation, quenching heated oil feed to a temperature permitting maximum non-cracking of the feed by admixing a predetermined proportion of relatively cool recycle residuum distillation product therewith, the added residuum also serving as a heat carrier during the subsequent flash distillation step to provide for an increased depth of flashing without necessitating an increase in feed temperature; applicant's apparatus comprising a substantially horizontal elongated shell, baffles in said shell dividing it into a plurality of sections, conduit means for introducing feed into an end section of the said shell in a direction toward the shell end thereof, preferably against a wire mat therein, spray means in the opposite shell end section, vacuum producing means in direct communication with the interior of the said opposite shell end section and outlet conduit means in each of the said shell end sections.

The temperature to which oil is quenched in the bottom of the hot oil separator is generally in the range of 650° to 830° F., depending upon the refractoriness of the particular oil being processed.

As vapors pass through baffles 14 and 16 the tortuous path provided by them serves to coalesce or remove a substantial portion or all of the entrained liquid droplets from the vapor stream. The removed liquid flows from the baffles to the bottom of the flash distillation vessel.

I claim:

1. In the recovery of condensed product of vacuum distillation and further utilization of a portion of same as feed to a conversion step requiring a constant feed inlet rate, the improvement comprising continuously withdrawing and collecting such condensed product from the zone of said distillation, continuously passing a portion of the collected condensate to said utilization at a predetermined constant rate controlled by the operation of an automatic flow control means, and continuously passing another portion of said collected condensate to said distillation zone in admixture with fresh feed thereto at a rate controlled in response to liquid level of the body of collected liquid.

2. In a process for the vacuum distillation of oils wherein oil to be distilled is preheated to a temperature approximating that at which incipient oil cracking occurs and is then charged to a vacuum flashing zone, the improvement comprising withdrawing a stream of unvaporized oil from the zone of said flashing and admixing same with oil heated as above described in proportions to quench said heated oil to a temperature below that at which incipient cracking of same occurs and passing the resulting admixture to said vacuum flashing zone, whereby the presence of light cracking product in the vacuum distillation feed is prevented and higher vacuum is obtained during said flashing, and oil admixed with said feed acts as a heat carrier to provide for an increased depth of flashing without the need for an increase in feed temperature.

3. A vacuum distillation process comprising heating an oil to be vacuum distilled, to an elevated temperature; passing oil thus heated into a separation zone to separate any vapors therefrom; withdrawing unvaporized oil from said separation zone together with residual distillation product admixed therewith as described hereinafter; introducing oil thus withdrawn into a vacuum distillation zone under flashing conditions so as to vaporize a portion of same, resulting residuum oil settling in said distillation zone; condensing vapors formed during said flashing and recovering resulting condensate; passing a portion of oil residuum from the zone of said flashing into admixture with heated oil in said separation zone in an amount and at a controlled rate of flow so as to quench said heated oil therein to a temperature below which incipient cracking of same takes place, and to act as a heat carrier during said flashing; and recovering a remaining portion of said residuum.

4. The process of claim 3 wherein said residuum oil is introduced into admixture with said heated oil at a point in close proximity to the point of withdrawal of said heated oil from said separation zone.

5. The process of claim 3 wherein a side stream of heated oil is withdrawn from said separation zone, cooled, and then recycled into said separation zone so as to supplement said quenching.

6. The process of claim 3 wherein the said amount of oil residuum admixed with heated oil is from 0.2 to 1.5 volumes per volume of said unvaporized oil withdrawn from said separation zone.

7. A vacuum distillation chamber comprising a closed

10 elongated shell; a first conduit extending into said shell and terminating in a first end section thereof; a first baffle transversely closing said shell and terminating the said first end section; a second baffle in said shell intermediate said first baffle and the shell end opposite said first 15 end section, and terminating a second shell end section, and together with said first baffle defining a central shell section; spray means in said second end section directed toward said second baffle; dam means associated with each of said baffles to prevent flow of liquid within said 20 shell from any one of said shell sections into another shell section; vacuum producing means external to said shell, in direct communication with the interior of said second end section; a surge drum connected with an outlet conduit from said second end section; outlet conduit 25 means in a side wall of said surge drum; a second conduit, connected with a surge drum outlet conduit; a third conduit, connected with a surge drum outlet conduit; means for controlling liquid flow from said surge drum through said second conduit in response to liquid level in said surge drum; and means for controlling flow of liquid from said surge drum through said third conduit at a predetermined constant rate, said surge drum having a much smaller horizontal cross sectional area than said second end section.

30 8. Apparatus comprising a distillation chamber; a liquid outlet surge drum connected with a liquid collecting section of said chamber; a first conduit in communication with the interior of said drum at a predetermined point therein so as to convey liquid flow from said drum; a second conduit in communication with the interior of said first conduit; means for controlling flow of liquid through said second conduit at a predetermined constant rate; and means for controlling flow of liquid through said first conduit in response to a level of said liquid 35 in said drum; said surge drum having a much smaller capacity and horizontal cross sectional area than said liquid collecting section.
